UNITED STATES PATENT OFFICE.

JAMES BURKE, OF ERIE, PENNSYLVANIA, ASSIGNOR TO BURKE ELECTRIC COMPANY,
A CORPORATION OF PENNSYLVANIA.

CURRENT-COLLECTING DEVICE.

Application filed August 30, 1923. Serial No. 660,103.

This invention relates to current collecting devices such as commutators and collectors adapted for use in dynamo electric machines. A primary object of my invention is to provide an improved means and method for reducing to a minimum the heating of brushes, commutators, collectors and associated parts by reason of friction at the collecting surfaces and for other causes. One of the important results attained by use of such means and method is to greatly increase the current carry capacity of the collecting device.

In the improved construction, designed in accordance with my invention, provision is made for absorbing and carrying away heat from the parts which it is desired to maintain cool, by causing a large volume of cooling air to pass in contact with or adjacent to these parts, and in the particular embodiment of my invention here illustrated, this cooling air is caused to pass along the surface of the commutator and adjacent to and along the commutator brushes.

My invention is particularly adapted for use in dynamo electric machines wherein the commutator rotates at a high peripheral speed. In such machines, unless special provision is made for dissipating the heat generated, the friction of the brushes together with other sources of heat such as the electrical resistance losses at the contact surfaces of the brush and commutator will cause such a rise in temperature as will seriously interfere with the effective operation of the commutator and ultimately destroy its utility. My invention is also adapted for embodiment in a structure which will be suitable for use in such places as cement mills, where in the past the use of collectors have been accompanied by disadvantages, due to the presence of hard particles in the air, which became lodged on the contact surfaces of the collectors, and caused an excessive abrasion of these surfaces. By causing air to move at a sufficient velocity along the contacting surfaces, the abrasive particles may be prevented from lodging thereon.

Further objects and advantages of my in-

vention than those above mentioned will appear from the following description taken in connection with the accompanying drawings which show one embodiment of my invention and wherein—

Fig. 1 is a sectional view of the commutator of the dynamo electric machine and shows in elevation a brush holder constructed in accordance with my invention.

Fig. 2 is a sectional view taken on the line 2—2 of Fig. 1 and shows a portion of the structure for supporting the brush holders as well as the means employed for creating an artificial circulation or draft of air.

Fig. 3 is a sectional view taken on the line 3—3 of Fig. 2.

In the drawing 10 represents a shaft of the dynamo electric machine journaled in suitable bearings in a stationary supporting member 11. The shaft 10 carries a commutator 12 which is formed of conducting segments 13 which are suitably held and supported by members 14 and 15 in a manner well known in the art. The segments are suitably spaced from one another by insulating strips and connectors 15' serve to connect the commutator segments with the rotor windings.

A brush holder 18 is supported from the member 11 by means of a member 16 which comprises two rings 55 and 56 encircling the shaft 10 of the dynamo electric machine and joined to one another by arms 57. Interposed between the ring 56 and the brush holder 18 is an insulating member 17 of arcuate form as shown in Fig. 1.

The machine illustrated is adapted to employ four brush holders similar to the one shown and the arcuate insulating members 17 each subtend 90° so as to form a circular baffle, the function of which will be particularly pointed out hereafter.

The brush holder comprises a body 19 preferably formed of cast brass. This casting comprises a supporting plate or yoke member 20 perforated at 21 and 22 for attachment to the bracket 16, there being suitable insulating bushings, not shown, for insulating the attaching bolts, and extending outwardly from the supporting plate 20 at 100

approximately right angles thereto is a portion 24 formed with an opening 25 for the reception of the commutator brush 23. The brush is normally maintained in engagement with the commutator by means of fingers 27 which are pivoted to the portion 24 of the casting 19 and are forced against the end of the brush by means of springs 28. One end of each spring engages the finger 27 at 30 and the other end is secured to a shaft 31. One of the shafts 31 is pivoted in a lug 32 formed integral with the portion 24 of the casting and in a central lug 33 likewise formed integrally with the portion 24. The other shaft 31 is pivoted in the central lug 33 and also in a connecting web member 35 which forms one wall of a recess 36 in the supporting plate 20. The shafts 31 have fixed thereto worm wheels 37 which engage with worms 38 carried by the lug 32 and the web 35. The worms 38 are provided with knobs or handles 39 through which the worm may be turned and the tension of the springs 28 adjusted.

25 The central lug 33 is formed with a screw threaded opening 43 for reception of the bolt which is adapted to clamp the brush pigtail to the casting 19 and so insure electrical contact between the brush and casting.

30 The lug 33 is also formed with an opening 44 to receive the lead from the external line.

35 The member 24 of the casting 19 at each side of the opening 25 is formed with elongated passages 46 which are joined by an opening 47 formed in the supporting plate 20. This opening 47 communicates directly with the space 49 between the brush holder 18 and the casing 11. The arcuate baffle 17 is cut away at this point to provide free communication between the opening 47 and space 49.

40 Suitably supported by the member 15 and adapted to rotate with the shaft 10 is a plate 50 carrying fan blades 51 which are adapted to draw air from the space 49 and discharge the same outwardly through and between the arms 57. It will be thus seen that the air around the commutator segments will be drawn into the passages 46 in a manner similar to that occurring in a vacuum cleaner. The openings to the passages 46 function much like vacuum cleaner nozzles. The air which is passing along the surface of the commutator will be drawn away from this surface at a high velocity through the nozzle openings of the passages 46. This air will then pass to the connecting opening 47 in the plate 20 and be drawn by the fan blades 51 outwardly into the space 49 or chamber 49 and from thence forced into the outer air. In this manner a constant current of air is maintained in contact with the segments and the contacting edges of the brushes and likewise through the metal brush holder in such a manner that heat

generated by friction of the brushes with the commutator segments or by sparking or otherwise will be quickly dissipated. The insulating members 17 serve as a baffle to form a passage for the outgoing air so as to cause a sufficient amount of the air to be drawn through the passages 46 instead of being drawn directly from the surface of the commutator into the space 49. The general directions of the currents of air are indicated by arrows on the drawing.

50 Instead of providing a plurality of members 17, the baffle may be formed of a single circular member surrounding the shaft 10 or if desired, the ring 56 may be extended inwardly to form the circular baffle. In the latter case, the insulating members 17 would not extend beyond the limits of the brush holder.

55 By reversing the connections between the fan and passages 46, or if desired by employing a blower in communication with the chamber 49 it is possible to reverse the direction of flow of air through the passages 46 of the brush holder. Such a blower may, for certain purposes, be supplied with pure air from any suitable source.

60 While in the embodiment of my invention here illustrated, I disclose the "vacuum nozzles" as parts of the brush holders, it will be understood that if desired, separate nozzles may be employed, which may be suitably located with reference to the surface of the commutator or other parts.

65 By the use of my invention it is possible to design machines with shorter commutator segments than now employed and by employing a requisite pressure on the brushes still maintain an effective contact with the commutator segments.

70 I claim:—

1. A brush holder formed with a brush receiving opening and an opening adjacent thereto and extending substantially the full length of one side of said brush receiving opening, said latter opening being adapted to form a passage for a cooling current of air.

75 2. In a dynamo electric machine a brush holder formed with a brush receiving opening and openings adjacent to and spaced from said brush receiving opening, said latter opening being adapted to form air passages and means for causing cooling currents of air to flow through said passages.

80 3. A dynamo electric machine having a rotary shaft, a brush holder formed with a brush receiving opening and air conducting passages adjacent to and spaced from said brush receiving opening and means supported by and rotating with said shaft for causing cooling currents of air to flow through said passages.

85 4. A dynamo electric machine having a commutator, brush holders each formed

with an opening and a brush located in said opening, said holder being formed with air passages adjacent to said opening, means for causing a cooling current of air to flow circumferentially along the surface of said commutator and through said passage and means for causing a cooling current of air to flow along the surface of said commutator in an axial direction between said brush holders.

5. A dynamo electric machine having a shaft, a commutator, a brush holder formed with an opening and a brush located in said opening and bearing upon said commutator, said holder being formed with air passages adjacent to said opening and a fan actuated by said shaft for causing cooling currents of air to flow along the surface of said commutator adjacent to the points of contact of said brush with said commutator and thence through said passages.

6. A dynamo electric machine having a shaft, a commutator, a brush holder formed with an opening and a brush located in said opening and bearing upon said commutator, said holder being formed with air passages at opposite sides of and adjacent to said opening and a fan supported by said shaft for causing cooling currents of air to flow along the surface of said commutator adjacent to the points of contact of said brush with said commutator and thence through said passages.

7. In a brush holder a body portion formed with a brush receiving opening of approximately rectangular section, said body being also formed with air passages spaced from said opening and extending through said body portion at opposite sides of said opening.

8. In a dynamo electric machine a commutator, a brush holder having a body portion formed with a brush receiving opening of approximately rectangular section, said body portion being also formed with air passages extending through said body portion at opposite sides of said opening, said passages terminating in elongated openings adjacent to the points of contact of said brush and commutator.

9. In a dynamo electric machine a commutator, a brush holder having a body portion formed with a brush receiving opening of approximately rectangular section, said body portion being also formed with air passages extending through said body portion at opposite sides of said opening, said passages terminating in elongated openings adjacent to the points of contact of said brush and commutator, and means for causing air to pass across the surface of said commutator and thence through said passages.

10. A brush holder having a body portion formed with a brush receiving opening of

approximately rectangular cross section and air passages extending through said body portion and having extended walls adjacent three sides of said opening.

11. A brush holder having a body portion formed with a brush receiving opening of approximately rectangular cross section, air passages extending through said body portion and having extended walls adjacent three sides of said opening, and means for causing air to circulate through said passages.

12. The combination with a casing of a dynamo electric machine having a commutator, brushes and brush holders located in said casing, said brush holders each being formed with passages terminating at one end adjacent the surface of said commutator and at the other end at a side of the brush holder adjacent the casing, a fan intermediate said casing and brush holder adapted to draw air along the surface of said commutator through said passage and to discharge the same outwardly in said casing.

13. A dynamo electric machine having a rotor, a commutator, brushes and brush holders, said brush holders being formed with air passages which terminate at one side thereof, a fan secured to said rotor and located adjacent the said side of said brush holders and a baffle located between the fan and the other terminals of said passages whereby said fan causes a circulation of air through said passages.

14. A dynamo electric machine having a rotor, a commutator, brushes and brush holders, said brush holders being formed with air passages which terminate at one side thereof, a fan secured to said rotor and located adjacent the said side of said brush holders and a circular baffle extending around the dynamo electric machine shaft and located between the fan and the other terminals of said passages whereby said fan causes a circulation of air through said passages.

15. A method to be employed in connection with the operation of a commutator, which comprises causing a sheet of air to pass circumferentially along the surface of the commutator and withdrawing said sheet from the vicinity of said surface at a high velocity.

16. A method to be employed in connection with the operation of a commutator comprising causing a current of air to be directed circumferentially along the surface of a commutator and to be withdrawn from said surface through narrow elongated openings.

17. A method to be employed in connection with the operation of a commutator comprising causing a current of air to be directed along the surface of a commutator and to be withdrawn from said surface in a

direction approximately normal thereto through narrow openings, which are elongated in a direction substantially parallel to the commutator axis.

5 18. A method adapted to be employed in connection with the operation of a collecting device comprising a commutator,

brush and brush holder, which method comprises withdrawing air at a high velocity from the vicinity of the commutator surface 10 through narrow elongated openings in the brush holder.

JAMES BURKE.
